UNITED STATES PATENT OFFICE.

JESSE J. SPURGEON, OF LYMAN, OKLAHOMA.

TUBE-SEPARATING MACHINE.

Application filed December 21, 1925. Serial No. 76,941.

This invention relates to tube separating machines, designed primarily for use in connection with the separation of oil well tubings, but it is to be understood that a machine, in accordance with this invention, can be employed for any purposes for which it is found applicable, and the invention has for its object to provide, in a manner as hereinafter set forth, a machine of the 10 class referred to, for expeditiously separating or unscrewing oil well tubing of various diameters when desired.

Further objects of the invention are to provide, in a manner as hereinafter set forth, a tube separating machine, which is simple in its construction and arrangement, strong, durable, thoroughly efficient in its use, conveniently arranged with respect to the tubing to separate the latter, and comparatively inexpensive to set up.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications 25 can be resorted to which come within the scope of the claims hereunto appended.

In the drawings wherein like reference characters denote corresponding parts throughout the several views:

Figure 1 is a top plan view of a tube separating machine, in accordance with this invention.

Figure 2 is a section on line 2—2, Figure 1.

Figure 3 is a section on line 3—3, Figure 2.

Figure 4 is a section on line 4—4, Figure 3.

Figure 5 is a top plan view of the holder element for the driven gripper carrier and with said element in open position.

Figure 6 is a section on line 6—6, Figure 5.

Figure 7 is a vertical sectional view of 50 the driven gripper carrier.

Figure 8 is a section on line 8—8, Figure 2.

A tube separating machine, in accordance with this invention, can be driven by any 55 suitable means, and with the operating shaft of the machine having a universal

joint connection with the driving means therefor, and such universal joint connection will allow a diversity of positions with relation to the tubing to be separated. It 60 will be understood that the operation shaft for the machine can be driven from any suitable prime mover therefor and connected to such prime mover in any suitable manner, but as before stated as the machine 65 is generally used in the oil field, it is operated from a tractor and the operating shaft of the machine universally connected therewith.

The machine includes a portable support, which as illustrated consists of a frame formed of a pair of side members 1, 2, and a rear member 3 arranged between and secured to the rear ends of the side members 70 1, 2. The members 1, 2 and 3 are constructed from wooden beams, and arranged between the members 1, 2, intermediate the ends thereof, as well as being secured therewith, is an intermediate member 4, which 75 is also formed from a wooden beam. The frame further includes a front member 5, which is in the form of a metallic yoke-shaped strap of less height than the height of the members 1, 2, and is positioned to 80 abut against the lower portion of the forward ends of the members 1, 2, and further against the outer sides of these latter at the lower part of the forward end terminal portions thereof. The front member 5 is secured to the side members 1, 2 by hold-fast 85 devices 6. The front member 5, centrally thereof, is formed with a circular enlargement 7 provided with a vertically disposed opening 8 forming a socket to be presently 90 referred to. The elements 1 to 5 of the support constitute the top thereof and the latter is mounted upon supporting legs 9 of 95 appropriate height.

The side member 1, as well as the side 100 member 2, rearwardly with respect to the intermediate member 4, is formed with a lengthwise extending slot 10 arranged slightly above the longitudinal median thereof and the said side member 1, as well as the side member 2 is provided forwardly of the intermediate member 4 with a lengthwise extending slot 11. The slots 10 and 11 of one side member are arranged in alignment with respect to the slots 10 and 11 of the other side member. The intermediate member 4 is provided with a transversely extending opening 12 and which is positioned between 105 110

the transverse median of the member 4 and the side member 2. The side member 2 is furthermore provided with a lengthwise extending slot 13 below the slot 11, and said slot 13 at its rear registers with the opening 12 and further projects a substantial distance forwardly of the intermediate member 4. The slot 13 is lengthwise disposed with respect to the side member 2 and is arranged above that part of the front member 5, which is secured to the outer face of the side member 2. The slot 13 extends to near the forward end of the side member 2. The purpose of the slots 10, 11 and 13 and the opening 12 will be presently referred to. The side member 1, forwardly with respect to the intermediate member 4 and below the slot 11 therein, is formed with a lengthwise disposed slot 14 of less length than the slot 13 in the side member 2. The bottom wall of the slot 14 is in alignment with the bottom wall of the slot 13. The function of the slot 14 will be presently referred to.

Arranged over the portable support and slidably connected therewith is a platform 15 capable of being shifted forwardly and rearwardly with respect to the side members 1 and 2. The platform 15 is of greater width than the width of the top of the portable support, but is of less length than the length of said support. The platform 15 projects laterally from the side members 1 and 2 and in proximity to its rear is provided with a pair of depending supporting legs 16 which oppose the outer faces of the side members 1 and 2 and are of a length to extend to the slots 10 in said members. The legs 16 are connected together by an elongated headed bolt 17, having its head abutting the outer face of one of the legs 16 and its threaded end extended from the other leg 16 and carrying a securing nut 18. The bolt 17 extends through the slots 10 and carries a roller 19 of a length to extend from the inner face of one leg 16 to the inner face of the other leg 16, and said roller travels against the lengthwise walls of the slots 10 when the platform 15 is shifted.

Depending from the platform 15, in proximity to the forward end thereof, is a pair of supporting legs 20, which oppose the outer faces of the side members 1 and 2 and are of a length to extend to the slots 11. The legs 20 are connected together by an elongated bolt 21 which extends through the slots 11 and has its head abutting against one of the legs 20 and its threaded terminal projected from the other leg 20 and carrying a securing nut 22. Mounted on the bolt 21 is an elongated roller 23, which extends from the inner face of one leg 20 to the inner face of the other leg 20. The roller 23 travels against the lengthwise walls of the slots 11 when the platform is shifted. The forward shift of the platform 15 is arrested

by the forward end walls of the slots 10 and 11 and the rearward shift of the platform 15 is arrested by the rear end walls of the slots 10 and 11.

The platform 15 is manually shifted and for such purpose a shifting bar 24 is provided and which at its rear end is bent to surround the roller 19, as indicated at 25. The shifting bar 24 projects forwardly from the roller 19 and extends through the opening 12 and further projects a substantial distance from the intermediate frame member 4 and is pivotally connected, as at 26, to a lever arm 27 disposed transversely with respect to the top of the portable support. The lever arm 27 is pivotally mounted, as at 28, in the slot 14 and extends through the slot 13 and projects a substantial distance from the side member 2 to provide for the convenient manual operation thereof. When the lever arm 27 is swung forwardly on its pivot, the platform 15 is shifted in a forward direction with respect to the side members 1 and 2, and when the lever arm 27 is moved rearwardly on its pivot the platform 15 is carried in a like direction.

Arranged over the platform 15 is a horizontally disposed gear element 29 having its upper face formed with a circular row of bevelled teeth 30, and its outer edge provided throughout with vertically disposed cog teeth 31. The upper face of the platform 15, in proximity to the forward end of the latter, is provided with a boss 32, upon which is mounted the lower end of the hub 33 of the gear element 29. Projecting upwardly from the boss 32 is a bearing post 34, about which the gear element 29 revolves. The post 34 is threaded and carries a retaining nut 35 for the gear element 29, and the latter is bodily shifted with the platform 15. Secured to the upper face of the rear end of the platform 15 is an upstanding support 36, providing a bearing for the operating shaft 37 of the machine. The shaft 37 is journaled in the top of the support 36, projects forwardly therefrom and carries on its forward end a bevelled pinion 38, which meshes with the bevelled teeth 30 for the purpose of driving the gear element 29. To prevent the rearward shift of the operating shaft 37, it is provided with a collar 39 which abuts against the forward face of the support 36.

The gear element 29 is of such diameter as to project an appropriate distance forwardly of the platform 15. The operating shaft 37 is connected in any suitable manner to a prime mover therefor, such as a tractor, and the connection may be a universal one to permit of positioning the portable support to allow a diversity of positions with relation to the tubing to be acted upon.

The machine further includes a holder element for the driven die carrier, and said

element is formed of a front and a rear section, which are pivotally connected at one side and adapted to be detachably connected together at their other sides. The rear section comprises a semi-circular body portion 40, having its top edge formed with a rib 41 which is flush with the inner face of said body portion. The body portion 40 is cut away, as at 42, to provide a shoulder 43, and said body portion is furthermore formed with a socket 44 opening at the shoulder 43. A rib 45 is formed on the bottom edge of the body portion 40. Formed integral with the body portion 40, at the lower part thereof and projecting rearwardly therefrom, is a connecting arm 46, having inwardly extending end portions 47 which project towards and are formed integral with the outer face of the body portion 40. The inwardly extending portions of the connecting arm 46 space the major portion of the latter from and rearwardly of the body portion 40. The front section of the holder element consists of a semi-circular body portion 48 having its top and bottom edges provided with ribs 49, 50 respectively. The body portion 48 is cut away to provide a clearance for the shoulder 43 and further to form what may be termed an extension 51, which when the sections are secured together, has its bottom edge seating on the shoulder 43. The body portion 48 is furthermore provided with a vertically disposed socket 52 which when the sections are swung to abutting position is arranged in vertical alignment with the socket 44.

A slot 53 is formed in the body portion 48 which opens into the socket 52 and also at the outer face of the body portion 48. Arranged within the socket 52 is a spring controlled locking pin 54 adapted to engage in the socket 44 for detachably connecting the sections together. Carried by the locking pin 54 and projecting outwardly through the slot 53 is a headed stud 55, which extends in the path of the nose 56 of a releasing member 57. The body portion 48 is formed with a tapered opening 58 disposed at right angles with respect to the socket 52. The body portion 48 is furthermore provided on its outer face with an integral boss 59 formed with an opening 60, which communicates with the opening 58. Extending through the opening 60 and into the opening 58 is the stem 61 of a handle member 62. The inner end of the stem 61 carries a securing nut 63 which abuts against one of the walls of the opening 58 and further against the inner face of the boss 59. The releasing member 57 is carried by the stem 60 and in connection with the nut 63 couples the handle member to the front section of the holder element. The body portion 48 is furthermore provided with a pair of spaced apertured ears 64, between which

extends one end of the arm 46, and the said ears 64 are pivotally connected to the arm 46 by a pivot member 65.

When the front section of the holder element is swung to a position whereby the extension 51 will be arranged in superposed relation with respect to the shoulder 43, the pin 54 can engage in the socket 44 and detachably connect the sections together. The pin 54 will move to engage in the socket 44, due to the action of its controlling spring, when the nose 56 of the releasing member 57 is swung clear of the pin 55. When it is desired to release the sections of the holding element, the handle member 62 is revolved to the right, whereby the nose 56 will engage the stud or lug 55 and shift the pin 54 upwardly to clear the shoulder 43 and then the front section can be swung outwardly from the rear section or holding element.

A supporting bracket is provided for the holder element and which coacts with the connecting or coupling arm 46. The supporting bracket comprises a bar 66 formed at its rear end with a depending arm 67, which extends down through the opening 8 in the enlargement 7 of the front member 5 of the top of the supporting frame. The arm 67 is of a length greater than the height of the enlargement 7 and depends below the latter. The arm 67 has its lower terminal portion threaded and engaging therewith is a securing nut 68, which when in position abuts against the bottom edge of the enlargement 7, under such conditions detachably connecting the supporting bracket to the front of the portable support. Depending from the forward end of the bar 66, is a pair of spaced arms 69, 70, having a removable coupling plate 71 detachably connected to the lower ends thereof. The bar 66, in connection with the arms 69, 70 and plate 71 provides a vertically disposed slot 72' through which extends the connecting or coupling arm 46, whereby the holder element is connected with the supporting bracket and retained therein by the plate 71.

The driven gripper carrier, which is revolvably mounted in and supported by the holder element, consists of a pair of oppositely disposed semi-cylindrical sections, and as each of the sections is of the same construction but one will be described, as the description of one will apply to the other.

The said sections are generally referred to by the reference characters 72, 73 and each of which consists of a semi-circular stem 74 and a semi-circular head 75. The inner face of the stem 74 is flush with the inner face of the head 75, and the latter is of materially greater thickness than the thickness of the stem 74, whereby the outer face of the head 75 will be positioned a substantial distance from the outer face of the stem 74. The inner face of the head 75 is formed with a

horizontally disposed groove 76, which extends from one side to the other thereof, is of appropriate width and positioned centrally of the inner face of the head 75. The 5 groove 76 is separated lengthwise by a rib 76', integral centrally with the inner or vertical wall of said groove. The vertical face 76'' of the rib 76' is positioned inwardly with respect to the inner face of the head 10 75. The vertical face 76'' of the rib 76' is eccentrically disposed with respect to the inner wall of the groove 76 and also with respect to the inner face of the head 75 and constitutes a cam surface. The vertical face 76'' of the rib 76' is of such curvature to form at each end what may be termed a riser 77 and an intermediate lower part 77', see Figure 8. The rib 76' is of the same length as the length of the groove 76. The 15 rib 76' provides means for shifting a gripper member, to be presently referred to, in clamping position with respect to a tube to provide for the latter to revolve with the carrier for the purpose of separating or unscrewing the same. The head 75 has its outer face provided throughout with cog teeth 78, which extend from the upper to the lower end of the head 75, and the latter is furthermore formed with a socket 78' which 20 extends through the rib 76' and opens at the outer face of the latter. The wall of the socket 78' is threaded. The bottom edge of the head 75 is formed with a groove 79 for the reception of a rib at the top of one of 25 the sections of the holder element.

The stem 74 at the bottom thereof has projecting from its outer face an angle-shaped flange 80, which provides a groove 81 for the reception of a rib at the bottom of a 30 section of the holder element.

When the sections 72 and 73 of the gripper carrier are arranged in active position, a circular guide passage 82 is provided for the reception of the tubing, and further when said sections are in active position the heads 75 thereof provide a cog gear driven from the gear element 29 for the purpose of bodily adjusting the gripper members, to be 35 presently referred to, to clamp the tubing, and further for bodily revolving the tubing when clamped therewith by the gripper members, for the purpose of separating or unscrewing the tubing.

A pair of gripper members is employed 40 and each is mounted in a groove 76 and each of which is of a construction to straddle a rib 76'. The gripper members are indicated generally by the reference characters 83, 84 and each of which is semi-circular in contour and consists of a body portion 85 of less 45 length than the length of a groove 76, having its working face flush with the inner face of the head 75 and its rear face formed centrally with a lengthwise extending groove 86 for the reception of the rib 76', and

against the base of the groove 86 operates the cam face 76'' of the rib 76' for the purpose of forcing the gripper member in clamping engagement with respect to the tubing. The working face of the body portion 85 is formed with a recess 87 of substantial width and length and communicating with the recess 87, through the inner wall of the latter, is an oval-shaped slot 88 of less length and of less width than the 50 length and width of the recess 87. The recess 87, in connection with the opening 88, provides means to permit of bodily shifting the gripper member to clamping position with respect to the tubing. Extending 55 through the body portion 85 and threadedly engaging with the wall of the socket 78' is a headed retaining screw 89 having its head positioned within the recess 87 and its shank extending through the opening 88, and said screw in connection with the recess 87 and opening 88 provides means for slidably connecting the gripper member to the head 75 of a section of the carrier.

When the driven gripper carrier is mounted in the holder element, the sections of the latter surround the stem 74 of the carrier and the holder element is interposed between the head 75 and the flanges 80 of the carrier element. When the carrier, with the gripper member secured therein, is mounted in the holder element, the carrier can be revolved through the medium of the gear element 29, and when it is desired to revolve the carrier, the platform 15 is shifted forwardly until the cog teeth 31 of the gear element 29 engage with the cog teeth 78 of the head 75. After the gear element has been shifted to mesh with the carrier, the gear element is then revolved through the medium of the pinion 38 and the action of the teeth 31 of the gear element 29 with respect to the teeth 78 of the heads 75 will provide for the revolving of the carrier, causing thereby the gripper members to 100 clamp the tubing and revolve the latter in a direction to separate or unscrew the same.

By removing the nuts 18, 22, and 68, the machine can be divided into three parts so it can be easily handled by two persons. 115 The machine can be used and operated on a rig floor by one man, whereas it now requires three men to do the same work.

Although the machine is designed primarily for disconnecting tubes by unscrewing the same, yet it is to be understood that it can be employed for screwing tube sections together. When operating to disconnect a tube or tube section, the connecting arm 46 works up to the top of the slot 72, but when connecting a pair of tubes or tube sections together it is initially set at the top of the slot 72 and works downwardly.

It is thought the many advantages of a tube separating machine, in accordance with 130

this invention and for the purpose set forth can be readily understood, and although the preferred embodiment of the invention is as illustrated and described, yet it is to be understood that changes in the details of construction can be had which will fall within the scope of the invention as claimed.

What I claim is:—

1. A tube separating machine comprising a driven gear element, a shiftable supporting platform therefor, driving means for said element mounted on the platform, a holder arranged forwardly of the platform, a carrier revolubly mounted in the holder and provided with a passage for the reception of the tube to be separated, gripper members arranged within and shiftable by the carrier for clamping the tube, and said carrier and gear element having teeth for interengagement for operating the carrier when said platform is shifted to provide for the interengagement of such teeth during the operation of the gear element whereby the carrier during the revolving thereof will provide for the activity of the gripper members to carry the tube therewith and separate the same.

2. A tube separating machine comprising a driven gear element, a shiftable supporting platform therefor, driving means for said element mounted on the platform, a holder arranged forwardly of the platform, a carrier revolubly mounted in the holder and provided with a passage for the reception of the tube to be separated, gripper members arranged within and shiftable by the carrier for clamping the tube, said carrier and gear element having teeth for interengagement for operating the carrier when said platform is shifted to provide for the interengagement of such teeth during the operation of the gear element whereby the carrier during the revolving thereof will provide for the activity of the gripper members to carry the tube therewith and separate the same, a support, and means for slidably connecting the platform thereto.

3. A tube separating machine comprising a driven gear element, a shiftable supporting platform therefor, driving means for said element mounted on the platform, a holder arranged forwardly of the platform, a carrier revolubly mounted in the holder and provided with a passage for the reception of the tube to be separated, gripper members arranged within and shiftable by the carrier for clamping the tube, said carrier and gear element having teeth for interengagement for operating the carrier when said platform is shifted to provide for the interengagement of such teeth during the operation of the gear element whereby the carrier during the revolving thereof will provide for the activity of the gripper members to carry the tube therewith and separate

the same, a support, means for slidably connecting the platform thereto, and means for connecting the holder to the support.

4. A tube separating machine comprising a driven gear element, a shiftable supporting platform therefor, driving means for said element mounted on the platform, a holder arranged forwardly of the platform, a carrier revolubly mounted in the holder and provided with a passage for the reception of the tube to be separated, gripper members mounted in and shiftable to active position to clamp the tube on the revolving of the carrier, said carrier and gear element having teeth for interengagement to provide for the operation of the carrier when the platform is shifted to cause the intermeshing of said teeth during the operation of the gear element, and means for shifting said platform.

5. A tube separating machine comprising a driven gear element, a shiftable supporting platform therefor, driving means for said element mounted on the platform, a holder arranged forwardly of the platform, a carrier revolubly mounted in the holder and provided with a passage for the reception of the tube to be separated, gripper members mounted in and shiftable to active position to clamp the tube on the revolving of the carrier, said carrier and gear element having teeth for interengagement to provide for the operation of the carrier when the platform is shifted to cause the intermeshing of said teeth during the operation of the gear element, means for shifting said platform, a support, means for slidably connecting the platform thereto, and means connected to the support and to the platform for shifting the latter.

6. A tube separating machine comprising gripper members, a carrier formed of a pair of complemental sections each having its inner face provided with means for the reception and shifting of a gripper member to clamping position with respect to the tube to be separated to provide for the bodily revolving of the tube with the carrier to separate the same, a sectional holder for removably and revolubly supporting the carrier sections in abutting, active position with respect to the tube to be separated, a bodily shiftable driving means for the carrier, and said driving means and carrier having coacting elements to provide for the revolving of the carrier when said driving means is shifted to cause the coacting of said elements.

7. A tube separating machine comprising gripper members, a carrier formed of a pair of complemental sections each having its inner face provided with means for the reception and shifting of a gripper member to clamping position with respect to the tube to be separated to provide for the bodily revolving of the tube with the car-

rier to separate the same, a sectional holder for removably and revolvably supporting the carrier sections in abutting, active position with respect to the tube to be separated, a 5 bodily shiftable driving means for the carrier, said driving means and carrier having coacting elements to provide for the revolving of the carrier when said driving means is shifted to cause the coacting of said elements, a support, and means for slidably connecting said driving means to the support.

8. A tube separating machine comprising 15 gripper members, a carrier formed of a pair of complementary sections each having its inner face provided with means for the reception and shifting of a gripper member to clamping position with respect to the tube to be separated to provide for the 20 bodily revolving of the tube with the carrier to separate the same, a sectional holder for removably and revolvably supporting the carrier sections in abutting, active position with respect to the tube to be separated, a 25 bodily shiftable driving means for the carrier, said driving means and carrier having coacting elements to provide for the revolving of the carrier when said driving means is shifted to cause the coacting of said elements, a support, means for slidably connecting said driving means to the support, and means connected to the support and to the driving means to provide for the bodily shifting of the latter.

9. A tube separating machine comprising 30 a carrier provided with a passage for the reception of the tube to be separated and further provided with means for clamping the tube therewith to provide for the bodily 35 revolving thereof with the carrier to cause the separation of the tube, a holder for removably and revolvably supporting said carrier, a shiftable carrier driving mechanism normally free of engagement with the 40 carrier, said carrier and mechanism having coacting means for revolving the carrier when said mechanism is shifted to operatively engage the carrier, and means for bodily shifting said mechanism to and from 45 the carrier.

10. A tube separating machine comprising 50 a carrier provided with a passage for the reception of the tube to be separated and further provided with means for clamping the tube therewith to provide for the bodily 55 revolving thereof with the carrier

to cause the separation of the tube, a holder for removably and revolvably supporting said carrier, a shiftable carrier driving mechanism normally free of engagement 60 with the carrier, said carrier and mechanism having coacting means for revolving the carrier when said mechanism is shifted to operatively engage the carrier, means for bodily shifting said mechanism to and from 65 the carrier, and means mounted on the holder for releasably latching it to the carrier.

11. A tube separating machine comprising 70 a carrier provided with a passage for the reception of the tube to be separated and further provided with means for clamping the tube therewith to provide for the bodily 75 revolving thereof with the carrier to cause the separation of the tube, a holder for removably and revolvably supporting said carrier, a shiftable carrier driving mechanism normally free of engagement with the carrier, said carrier and mechanism having 80 coacting means for revolving the carrier when said mechanism is shifted to operatively engage the carrier, means for bodily shifting said mechanism to and from the carrier, a support for said mechanism, means for slidably connecting said mechanism to the support, and means connected to the support and said mechanism for shifting the latter to and from the carrier.

12. A tube separating machine comprising 85 gripper members, a sectional revolvable 90 carrier formed with a stem and a pinion at one end of the stem, said carrier further formed with a passage for the reception of the tube to be separated and means to receive and operate a pair of gripper members to clamp the tube to the carrier during the revolving of the latter to separate the tube, a sectional holder detachably connected to said stem and revolvably supporting the carrier, a gear element, a platform 95 for bodily shifting the gear element to mesh with the pinion to revolve the carrier during the operation of the gear element, driving means for said gear element mounted on the platform and bodily shiftable therewith, supporting means common to the platform and holder, and means connected with said supporting means and platform for shifting the latter.

In testimony whereof, I affix my signature hereto.

JESSE J. SPURGEON.
